RIGID SHEET METAL AWNING

Joseph W. Snider, Kenmore, and Stephen G. Domster, Buffalo, N. Y.; said Domster assignor to said Snider

Application December 29, 1948, Serial No. 150,424

Term of patent 14 years

(CL D21—6)

To all whom it may concern:

Be it known that we, Joseph W. Snider and Stephen G. Domster, respectively citizens of the United States, and residing, respectively, in Kenmore and Buffalo, in the county of Erie and State of New York, have invented a new, original, and ornamental Design for a Rigid Sheet Metal Awning, of which the following is a specification, reference being had to the accompanying drawings, forming part thereof.

In these drawings:

Fig. 1 is a perspective view of a rigid sheet metal awning embodying the present design.

Fig. 2 is a side elevational view thereof, the opposite side elevational view being substantially identical thereto.

Fig. 3 is a front elevational view thereof.

Fig. 4 is a top plan view thereof.

Fig. 5 is a rear elevational view thereof.

Fig. 6 is a bottom plan view thereof.

We claim:

The ornamental design for a rigid sheet metal awning, as shown and described.

JOSEPH W. SNIDER.

STEPHEN G. DOMSTER.
